DIE HEAD OPERATING MEANS

David R. Powell and William L. Moore, Cleveland,
Ohio, assignors to The National Acme Com-
pany, Cleveland, Ohio, a corporation of Ohio

Application August 19, 1943, Serial No. 499,172

10 Claims. (Cl. 10—95)

The present invention relates to threading tools such as taps and dies and more particularly to die head operating means, the principal object being the provision of improved means for opening, closing and resetting the chasers of a die and which is simple in construction, efficient and positive in operation and inexpensive to manufacture.

A further object of the invention is the provision of simplified means for opening the die to permit removal of the chasers without the necessity of dismantling the die and which is controlled by the same means that opens and resets the chasers.

A still further object of the invention is the provision of means for completely dismantling the die, likewise under the control of the same opening and closing means.

Heretofore, many different means have been employed for these various objects, such as fulcrumed levers, latches, etc., all of which have been more or less unsatisfactory and the present invention eliminates many defects while, at the same time, it combines into a single operating means the various desirable features hereinbefore set forth. Further advantages will be apparent from the following detailed description.

In the drawings accompanying and forming a part of this specification:

Fig. 1 is a perspective view of the die head unassembled.

Fig. 2 is an end view illustrating the chasers in place.

Fig. 3 is a perspective view of the operating member.

Fig. 4 is a partial section illustrating a chaser and block in open position.

Fig. 5 is a plan view of the die head illustrating the operating handle in closed position and in dotted lines the position of the handle when the head is opened.

Fig. 6 is a partly sectional view of Fig. 5.

Fig. 7 is an end view of Fig. 6 without the chasers.

Fig. 8 is a vertical section taken on the line 8—8 of Fig. 6.

Fig. 9 is a partly sectional view of the die head, illustrating the operating handle and die cut in position for removing the chasers.

Fig. 10 is a sectional view of the die head, illustrating its position when the chasers are open, and

Fig. 11 is a sectional view of the die head, illustrating the position of the operating means when

the head is being dismantled, as illustrated in Fig. 1.

Similar reference characters indicate corresponding parts in the several views.

Before explaining in detail the present improvement and its mode of operation, we desire it understood that the invention is not limited to the details of construction and arrangement of parts illustrated in the accompanying drawings since the invention is capable of other embodiments, and that the phraseology employed is for the purpose of description and not of limitation.

Referring now particularly to the drawings, this improved die head comprises a shank 2 for attachment to the usual holding means of a machine and this shank is provided at its front end with a body portion 3 having in the end thereof a series of radially located T-slots 4 for the reception of chaser blocks 5 carrying suitable chasers 6.

In the present instance, these chasers have been illustrated as circular but it is to be understood any other type of chaser may be employed since the chaser per se forms no part of the present invention. The blocks 5 have the usual pins 5' in engagement with suitable springs 5'' for shifting the chasers outwardly, the chasers being closed or collapsed when the body is forced into the die cup or cap 13 hereinafter referred to. This is due to the engagement of the front edge of the collar 13 with the beveled portion on the rear of each chaser block 5 as shown in Fig. 4.

The body portion 3 of the die head is provided at the rear thereof with a plate 7, suitably secured thereto, of substantially the same diameter as the body portion and in front of this plate the body is provided with a circumferential, peripheral slot 8 and in front thereof with a second circumferential, peripheral slot 9 somewhat deeper than the first slot, the purpose of both of which will be more fully described hereinafter.

Located in the rear of the body portion 3 and plate 7 is an adjusting ring 10 having a forwardly extending pin 11 extending into a bushing 12 located in the die body. The particular construction of this pin and bushing forms a part of a separate application filed August 19, 1943, Serial Number 499,174, and will not be described further herein.

Surrounding the body 3 is a die cup or cap 13 of a construction somewhat similar to that used in many threading patents of The National Acme Company, particular reference being had to the William J. Hogg Patent No. 1,952,205, except that, in place of the grooved collar 5 for

the reception of machine operating elements of that patent, improved hand operating means about to be described have been provided.

The die cup 13 in the present instance is provided with a threaded opening 19 for the reception of the operating means generally denoted by 14 (Fig. 3). This operating means 14 comprises a shank 15 having at one end a collar 16 provided with an eccentrically located pin or projection 17 and at its other end a handle 18 is secured thereto in any suitable manner.

The operating means is held in operative position by means of a suitable spring 20 bearing at one end against the collar 16 and at the other end against the shoulder of a hollow nut 21 threaded into the opening 19 of the cup 13.

Normally, when the die is assembled, the pin 17 is adapted to extend into the slot 9 of the die body 3 and held therein by the spring 20. In the particular form illustrated the handle 18 is so positioned relative to the shank 15 that it will extend toward the rear of the die body when the pin 17 is in the forward position. However, this position may be changed to suit conditions but, as illustrated in Fig. 10, when the handle is in the rearward position and the pin in the forward position, the die cup 13 is back on the die body 3 and the chasers are open.

It will be readily seen that, by turning the handle in a direction tangentially of the body through 90 degrees in either direction, the collar 16 will be rotated 90 degrees in a direction tangentially of the body. Since the eccentrically located pin 17 is rotatably secured in the circumferential slot 9 of the body and as the body is held against movement, the rotation of the collar 16 will cause the pin 17 to be rotated through 90 degrees to exert a lever action on the die cup to move it forward on the body to close or reset the chasers to the cutting position, as illustrated in Fig. 6.

When it is desired to remove the chasers from the die head, the operating means 14 is raised against the action of the spring 20 sufficiently to permit the pin 17 to raise out of the slot 9 and by sliding the cup 13 back, the pin will engage the slot 8 and abut against the collar or ring 7. This permits the chasers to be removed from the die head for grinding or any other purpose but maintains the remaining parts of the die in assembled condition.

Should it be desired to disassemble the entire die head for cleaning or any other purpose, the operating means 14 is raised further against the action of the spring 20 to permit the pin 17 to clear the collar 7 (Fig. 11) and the cup may be moved back to the position shown in Fig. 1.

Thus, it will be seen that we have provided a simple operating means for a die head which will enable the operator to open and close the chasers by a simple one-fourth turn of the operating handle and permits the chasers to be reset at the beginning of the threading operation and opened at the conclusion thereof in a very accurate manner. Likewise, this operating means enables the operator to open the die at any time during the threading operation should there be any necessity to do so to avoid injury to the chasers or for any other reason. It also enables the operator to move the cup back sufficiently to remove the chasers for grinding without dismantling the entire head and also to dismantle the die head when desired, both of which operations are under the control of the operating handle.

It is to be understood that by describing in detail herein any particular form, structure or arrangement, it is not intended to limit the invention beyond the terms of the several claims or the requirements of the prior art.

Having thus explained the nature of our said invention and described a way of constructing and using the same, although without attempting to set forth all of the forms in which it may be made or all of the modes of its use, we claim:

- 5 1. A threading die comprising a chaser-carrying body, a closing cap, one shiftable relative to the other, and means for effecting said shifting and comprising a rotatable member carried by the cap and having means engaging the body for effecting said shifting upon rotation of said rotatable member, and means located above said rotatable member for rotating it, said rotatable member and its rotating means rotatable on a common axis.
- 10 2. A threading die comprising a chaser-carrying body, a closing cap, one shiftable relative to the other, and means for effecting said shifting and comprising a rotatable member carried by the cap and having eccentrically located means 15 engaging the body for effecting said shifting upon rotation of said rotatable member, and means located above said rotatable member for rotating it, said rotatable member and its rotating means rotatable on a common axis.
- 15 3. A threading die comprising a chaser-carrying body, a closing cap shiftable on said body, means for shifting the cap relative to said body and comprising a rotatable arm carried by the cap and having eccentrically located means engaging the body for shifting said cap upon rotation of said arm, said eccentrically located means comprising a pin projecting into a peripheral slot in the body and resilient means for maintaining the pin in said slot, and yieldable to permit release of said pin from the slot to permit further shifting to dismantle said die.
- 20 4. A threading die comprising a chaser carrying body, a closing cap, one shiftable relative to the other, means operable in a rotary direction for effecting said shifting to open and close the chasers, and operable in a radial direction to permit further shifting thereby to remove the chasers, and yieldable means for normally preventing said radial movement.
- 25 5. A threading die comprising a chaser-carrying body, a closing cap, one shiftable relative to the other, an operating means rotatable to effect a limited shifting thereof to open and close the chasers, and spring-pressed means for maintaining said means in operable position and yieldable to permit movement in a radial direction to effect an increased limited shifting to permit removal of the chasers.
- 30 6. A threading die comprising a chaser-carrying body, a closing cap, one shiftable relative to the other, an operating means rotatable to effect a limited shifting to open and close the chasers, yieldable means for maintaining said means in operable position and to permit movement in a radial direction to effect an increased shifting to permit removal of the chasers, and means for limiting said last movement, said yieldable means also yieldable beyond said limiting means for permitting unlimited shifting to dismantle the die.
- 35 7. A threading die comprising a chaser-carrying body, a closing cap, one shiftable relative to the other, a rotatable and radially shiftable means for shifting one of said parts relative to
- 40
- 45
- 50
- 55
- 60
- 65
- 70
- 75

the other, said means shiftable in a plurality of opposite directions for opening and closing the chasers and shiftable in a radial direction to permit removal of the chasers and for dismantling the die, and yieldable means for normally preventing radial shifting of said shiftable means.

8. A threading die comprising a chaser carrying body, a closing cap, one shiftable relative to the other, means for effecting said shifting and comprising rotatable means carried by the cap and having means engaging the body for effecting said shifting, said rotatable means yieldably connected with the cap for transverse movement relative thereto, thereby to permit additional shifting movement of the body and cap, one relatively to the other to permit removal of the chasers.

9. A threading die comprising a chaser carrying body, a closing cap, one shiftable relative to the other, means for effecting said shifting and comprising rotatable means carried by the cap and having means engaging the body for effect-

ing said shifting, said rotatable means yieldably connected with the cap for transverse movement relative thereto, and a plurality of means carried by the body and cooperating with said body engaging means whereby on partially releasing the pressure on said body engaging means, the chasers may be removed and on further releasing the pressure, dismantling of the die may be effected.

10 10. A threading tool comprising a chaser carrying body, a closing cap, one shiftable relative to the other, shiftable means carried by the cap and having a yielding eccentric connection with the body for shifting said body and cap relative to each other, said body having a plurality of means cooperating with a part of said yielding eccentric connection whereby, on partially releasing the pressure on said eccentric connection, the chasers may be removed and on further releasing the pressure, the dismantling of the tool may be effected.
